DOOR OPERATING MECHANISM

Fred Lichtfeldt, Wauwatosa, Wis.

Application July 12, 1937, Serial No. 153,094

18 Claims. (Cl. 268—35)

(Cl. 268—35)

This invention relates to door operating mechanism and is particularly directed to mechanism for operating garage doors.

Objects of this invention are to provide a garage door operating mechanism which is so made that the driver can open the doors by hand when he is leaving and by this operation store a sufficient amount of energy in the mechanism as, for example, by lifting a relatively large weight, 5 may thereafter drive his car from the garage and operate a trip mechanism through the medium, for example, of a pull cord to release the mechanism and allow the doors to automatically close under the influence of the relatively 10 large weight, the descending large weight preferably storing a portion of the energy in the mechanism by raising a relatively smaller weight, which remaining portion of the energy is utilized 15 to subsequently open the doors so that upon returning the operator may operate the mechanism to open the doors without leaving his car 20 and may then drive into the garage.

and may then drive into the garage.

Further objects are to provide a construction in which means are provided for automatically temporarily locking the doors in open position until the trip mechanism is operated, in which means are provided for automatically closing and locking the doors closed, and in which means are provided for automatically unlocking the doors and opening them and again locking them in open position temporarily until released by the operator.

Further objects are to provide a construction in which the release mechanism may be operated from a pull cord, the mechanism being so arranged that a large amount of slack in the cord is provided so that the operator may grasp the cord as he drives from the garage, the slack allowing him to drive a sufficient distance to clear the doors and the trip mechanism having a delayed action and closing only after the slack of the pull cord has been taken up, the construction providing a slack take up mechanism to quickly withdraw the cord into the garage before the doors are automatically closed, suitable dash pot mechanism being provided to prevent shock particularly during the final portion of the opening motion of the doors.

Further objects are to provide a construction which is operated by the force of the automobile when the automobile is outside of the garage to release the mechanism and allow the doors to open, the construction being such that it is impossible for an unauthorized person to operate the mechanism by hand from the outside of

the doors as a considerable amount of force, such as supplied by the automobile, is required for the automatic release of the doors, opening means however being provided, such as a key operated mechanism, so that the authorized operator may manually release the latch and open the doors by hand from the outside. 5

A further object of this invention is to provide a construction so that the releasing mechanism may be operated by the automobile itself from the outside of the garage, the mechanism being so constructed that the amount of force required to release the mechanism may be adjusted to any desired value. 10

any desired article.

Further objects are to provide a construction which though mechanically operated and having the several functions hereinabove enumerated, is nevertheless relatively simple and may be cheaply constructed.

An embodiment of the invention is shown in 20 the accompanying drawings, in which:

Figure 1 is a fragmentary side elevation of the device.

Figure 2 is a side elevation, partly in section and partly broken away, showing the main carriage, the trip mechanism and the associated parts in door closed position. 25

Figure 3 is a plan view of the structure shown in Figure 2.

Figure 4 is a fragmentary view corresponding to Figure 1 and showing the parts in door open position. 30

Figure 5 is a detail of the auxiliary carriage.
Figure 6 is a detail of one of the latches.

Figure 7 is a sectional view on the line 7-7 of Figure 8. 35

Figure 8 is a fragmentary view of the doors taken from the inside of the garage.

Figure 9 is a fragmentary sectional view on line 9-9 of Figure 8. 40

Figure 10 is a fragmentary sectional view on the line 10-10 of Figure 8.

Figure 11 is a fragmentary view, partly in section, of the automobile operated release means. Figure 12 is a fragmentary plan view of the mechanism showing the doors in closed position in full lines and in open position in dotted lines.

Figure 13 is a sectional view on the line 13—13 of Figure 2.

Figure 14 is a detail, partly in section, showing the slack take up means for the pull cord. The major portion of the mechanism is carried by a pair of guide rails or tracks 1 which are supported adjacent their front end by means of a bracket 2 secured to the stationary frame 3.

adjacent the doors 4. These rails may conveniently have reversely turned portions 1' which are secured by means of a bolt 5 to the bracket, the bracket having down turned fingers 6 on opposite sides of the rails to assist in positioning the rails. If desired, the bolt may have a square portion located between the rails, as indicated in Figure 3.

The rear portions of the rails are supported by means of the hanger member formed of the strap metal loop 7, see Figures 1, 2, 3 and 13, which is suspended by means of the wire 8 from the upper portion of the garage, see Figure 2. This support has a lower flat bottom portion passing beneath the rails, as shown in Figure 13, and has slotted corners 9 through which a horizontal bracing wire 10 is passed, the bracing wire being positioned between the horizontal portion 11 of a bracket 12, see Figure 2.

20 The bracing wire 10 is clamped between the portion 11 of the bracket and the strap hanger 7 by means of a bolt 13 which is provided with a square nut 14 located between the rails and serving as a spacer therefor. Preferably tongues 15 are turned up from the portion 11 to engage the rails on their outer sides, as shown in Figure 13. This construction allows lateral adjustment of the rear portion of the guide rails to insure the correct adjustment of the parts. The bracket 25 12 is additionally secured to the rails 1 by means of the bolt 12', see Figures 2 and 3.

A main carriage is slidably mounted on the guide rails or tracks and includes a bolt or rod member 16 which extends vertically through an upper sleeve 17 and a lower sleeve 18. The carriage also includes an upper and a lower plate 19 and 20 positioned on opposite sides of the guide rails and having the bolt 16 passing therethrough.

40 The upper plate 19 preferably has downwardly turned side flanges located on opposite sides of the rails.

The carriage also includes a front latching member 21 and a rear latching member 22. The upper sleeve 17 is connected with one of the doors by means of the operating rod or link 23 and the lower sleeve 18 is connected by means of the operating rod or link 24 with the other door, the rods being adjustable as to length, as indicated in Figure 12.

50 An auxiliary carriage 25 is also provided and is guided by the guide rails 1 and located inwardly of the main carriage. It is shown in detail in Figure 5 and has an upper plate 26 and a lower plate 27 connected by a web 28 and provided with a tongue 29 and with a pair of catches forming ears 30 which are struck upwardly, all the parts being formed integral. A screw 31, see Figure 2, is threaded into the lower plate and provided with a lock nut so that the spacing of the plates 26 and 27, see Figure 5, may be adjusted.

60 The ears 30 are engaged by the rear latch 22 at one position in the operation of the apparatus and are so shown in Figure 2. The front latch 21 is inoperative except when the doors are open. When the doors are open, it is obvious that the main carriage is at the front of its travel and the front latch 21 engages the front catch 32, see Figure 2, the front catch being formed by 70 a pair of cam shaped members slanting rearwardly and having abrupt forward faces behind which the fingers of the front latch 21 drop.

Figure 6 shows a detail of one of the latches, for example the rear latch 22, the latches being substantially duplicates and being provided with

downwardly extending tongues 33, see Figure 6, which are positioned on opposite sides of the guide rails 1, as may be seen from Figure 2.

The bottom plate 27 of the auxiliary carriage 25 contacts the bracket 12, see Figure 2, the bracket 12 acting as a stop to limit the rearward motion of the auxiliary carriage.

The relatively heavy weight is attached to the chain 34 and the relatively lighter weight is attached to the chain or other member 35, the chain 35 passing over the front pulley 36 pivotally carried by a bracket and attached to the under side of the rails 1, as shown in Figure 2, the chain 35 extending to the main carriage, as shown in Figures 2 and 3. From the main carriage a chain 35' extends to a dash pot herein-after described. A headed rod or bolt 37 passes through the ear 38 of the front bracket and is locked in place by a nut, as shown in Figures 2 and 3. This rod or bolt forms the axis of the front trip lever 39 which is provided with an upwardly projecting arm 40 connected by means of a link 41 with the rear trip member 42, such rear trip member being pivoted to the bracket 12 and being normally held in a retracted position by means of the spring 43, as shown in Figure 2. The operation, therefore, of these two trip members is simultaneous though in opposite directions, the rear trip member being adapted to trip the rear latch 22 and the front trip member being adapted to trip the front latch 21 when the front latch is locked behind the catch 32. A pull rod 44 is provided and attached to the front trip member 39 and extends rearwardly through a guiding ear 45 formed on the bracket 12, suitable stops 46 being provided on the rod to limit its motion in each direction, see Figures 2 and 3.

The rod is attached to the pull cord 47, see Figure 1, and this pull cord extends rearwardly over the pulley 48, see Figures 1 and 14. The pull cord passes over a pulley 49 which carries a flat weight 50 which is positioned, as may be seen in Figure 1, closely adjacent the rear wall 51 of the garage so as to prevent the pulley 49 from rocking out of its correct position when the weight 50 is raised and lowered in a manner hereinafter to appear. The pulley 49 in reality is a sheave pulley and is provided with a contacting face 52 adapted to engage a stop 53 carried by the bracket 54 that supports the pulley 48, see Figure 14. A second pulley 55 is also supported from the bracket. From the second pulley 55 the pull cord 47 extends through a fixed eyelet or pulley 56, see Figures 1 and 12, and hangs downwardly, as shown in Figure 1, and is provided with a weighted end 57 which may be grasped by the driver as the car is moving out of the garage.

It is apparent from the description thus far given that when the pull cord 47 is pulled a considerable amount of slack may be withdrawn, as the weight 50 is merely lifted, see Figures 1 and 14. However, when the member 52 contacts the stop 53, the pull cord then becomes taut and rocks the trip members 39 and 42 to tripping position, the trip members working simultaneously though in opposite directions as described, and these trip members will trip the front or the rear latch, as the case may be, to release the main carriage either from the front catch 32 or from attachment to the auxiliary carriage 25.

It is obvious that as the main carriage moves forwardly, that the chain 35', see Figure 2, which extends to the dash pot mechanism 58, see Fig-

ure 1, will be tightened and will take up the slack, as shown in Figure 1, a suitable weight 59 being provided to maintain the horizontal portion of the chain 35' taut, the forward travel of 5 the carriage at the latter portion of its stroke being thereby retarded and thus retarding the final opening motion of the doors to prevent shock or jar.

Additional means are provided for operating 10 the trip mechanism from the outside of the garage. This means comprises a bowed spring 60, see Figures 1 and 11, which is held in spaced relation to the door 4 and is provided with a padded portion 61 adapted to be struck by the 15 bumper of the car when it is desired to have the doors automatically open. The spring 60 is a very heavy spring and cannot be operated by a person pressing against it but can be operated by driving the bumper of the car against the 20 spring. The motion of the heavy leaf spring 60 is transmitted by means of the rod 62, see Figure 11, which extends through the door and is guided by a bracket 63. The end of the rod 62 has bolted thereto a bifurcated clip 64 into which 25 a link of the chain 65 is secured. The chain is connected with the cable 66, see Figures 1, 8 and 11, and this cable connects with the bottom looped end of the rod 67, as shown most clearly in Figures 8 and 9.

30 The upper end of the rod is connected to an arm of a bell crank lever 68, see particularly Figures 3 and 9, pivotally supported from the door 4 and this bell crank lever is adapted to engage a pin or abutment 69 carried by the front 35 trip member 39, as may be seen from Figures 3, 8 and 9, the front and rear trip members being of U-shape, as shown most clearly in Figure 3.

It is obvious, therefore, that when the spring 40 60 is pressed inwardly by means of the bumper 45 of the car, that the rod 67 is pulled downwardly and the trip mechanism is operated. The rod 67 is provided with a looped portion which slants upwardly, as indicated at 70 in Figures 8 and 10, which normally bears against the shank 71 of 45 an eyelet or headed member carried by the door; the rod is also provided with a horizontal portion 72 which extends through a loop or eyelet formed in a rod or other member 73 connected to the plunger of the door catch indicated generally at 74 in Figure 8, such catch locking the 50 door in closed position in the customary manner. The horizontal portion 72 of the rod 67 is connected by means of a cord 75 with a fixed member 76 carried by the frame work of the 55 door, as shown in Figures 8 and 12. Additionally the rod 73 is connected to the arm 77 of a key operated member, the shank 78 of which, see Figure 7, is threaded into the door and provided with a slot 79 adapted to receive a correspondingly shaped key.

Obviously another type of mechanism could replace that shown in Figure 7 more on the order of a conventional lock if desired provided a movable portion of the lock is connected to the rod 65 73 to withdraw the plunger 74 when the lock is released.

The relatively heavy and relatively light weights hereinbefore referred to are shown most clearly in Figure 1 and indicated by the reference characters 80 and 81 respectively, the respective chains or other flexible members 34 and 35 extending over pulleys 82 and 83 respectively attached to the rear portion of the garage.

The operation of the apparatus is as follows: 75 Assuming that the automobile is in the garage

and the driver desires to unlock the doors, he merely inserts his key, not shown, in the slot 79 and rotates the arm 77, see Figures 7 and 8, thus withdrawing the plunger of the latch 74 and allowing him to open the doors. However, the 5 latch 74, see Figure 8, is locked in retracted position for the horizontal portion 72 of the rod 67 will slide beneath the member 71, see Figures 8 and 10, and thus hold the latch in retracted position. However, as the doors complete their opening stroke, the cord 75 tightens and withdraws the horizontal portion 72 or locking portion of the rod 67 from the member 71 and releases the catch 74 so that it is again in condition to snap into locking position when 15 the doors are closed, the latch 74 being the ordinary type of spring latch.

Motion of one door will cause simultaneous 20 motion of the other door through the medium of the connecting rods or links 23 and 24 and the main carriage, as is obvious from Figures 2, 3 and 12. During this operation the main carriage moves forwardly and pulls the auxiliary carriage 25 with it, thus raising the heavy weight 25 89 and lowering the light weight 81, the auxiliary carriage being temporarily attached to the main carriage by means of the rear latch 22 of the main carriage, see Figure 2. When the doors are completely opened, the front latch 21 of the main carriage, see Figure 4, latches over the 30 catch 32 on the guide rails 1 and thus locks the doors open. The driver now enters his car and drives from the garage. In passing out of the garage, he catches the pull cord 47, see Figure 1, and holds this cord as the car moves from the 35 garage. When all the slack in the pull cord is taken up, the trip members 42 and 39 are simultaneously operated, though the trip member 42 performs no function at this time. The front trip member 39, however, lifts the front latch 21 40 of the main carriage from the catch 32 and allows the heavy weight to pull the auxiliary carriage and main carriage rearwardly. This thus pulls the main carriage rearwardly and closes the doors. However, before the doors can close 45 due to their inertia, it is obvious that the slack take up mechanism for the pull cord will have operated and the pull cord is immediately drawn into the garage prior to the closing of the doors. It is to be noted that the ordinary door latch 74 50 is in condition to operate and to thus lock the doors closed.

Upon returning to the garage, the driver causes the bumper of the automobile to strike the padded portion 61 of the leaf spring 60, see Figure 11, thus pressing the plunger 62 inwardly and pulling the members 65 and 66 downwardly, it being noted that a spring 65' is interposed between such members. This draws the rod 67 downwardly and causes the bell crank lever 68, see Figure 9, to move the trip members to tripping position. The front trip member 39, see Figure 2, performs no function at this time but the rear trip member 42 lifts the rear latch 22 of the main carriage from the auxiliary carriage and this allows the main carriage to move forwardly under the influence of the light weight. The downward motion of the rod 67 also moves the rod 73 downwardly and thus withdraws the spring catch 74 from door locking position. It is locked in this 70 position due to the fact that the horizontal portion 72 of the rod 67 has now passed beneath the member 71, see Figure 10. The forward motion of the main carriage opens the door and as the doors near full open position, the chain 35' 75

is retarded by the dash pot mechanism 58, see Figure 1, thus retarding the final opening motion of the doors. The front catch 21 now latches to the front latch 32, see Figure 4, and holds the doors open allowing the driver to drive the car into the garage. Thereafter the driver trips the trip mechanism through the medium of the pull cord and manually closes the doors.

In addition to the main functions hereinabove described, it is to be noted particularly that the force required to automatically open the door by deflecting the heavy spring 60 may be adjusted by adjusting the point at which the chain 65 hooks into the catch 64, see Figure 11.

15 It is obvious that if a considerable amount of slack is provided, that the leaf spring 60 has to travel through a considerable stroke to release the mechanism, whereas a tighter adjustment of the chain with less slack will require a lesser stroke 20 of the relatively heavy leaf spring 60, under all conditions the spring 65' preventing breaking of the parts due to over travel of one with reference to the other.

25 It is to be understood that although the swinging type of garage door has been shown, it is obvious that other types of doors can be operated by this apparatus.

30 It will be seen that a novel form of garage door operating mechanism has been provided by this invention in which there is a definite cycle of operations, the initial opening of the doors by the operator storing a sufficient amount of energy by the lifting of the large weight so that this energy may be employed in two distinct intervals—first, for the automatic closing of the doors and second, for the automatic opening of the doors, so that after the driver is in his car within the garage, he does not have to alight from his car to operate the doors either to close them when 40 he leaves the garage or to open them when he returns.

45 Additionally, it is to be noted that there is no chance of damage to the car due to the blowing shut of the door while the driver is entering or leaving the garage, as the doors are locked in open position by the automatic mechanism. Additionally, whenever the doors are closed, they are locked in closed position and it is obvious that the doors may be unlocked from the outside, as has been heretofore described, or from the inside of the garage by merely pulling downwardly on the rod 73, see Figure 8.

50 It will be seen that a relatively simple mechanical device has been provided for accomplishing the functions hereinabove set forth.

The invention is applicable for the operation of either a single door or of a pair of doors, the latter having been shown for the purpose of illustration. It is therefore intended that neither the word "door" nor the word "doors" is intended to limit the invention either to a single door or to a pair of doors.

55 It is to be noted particularly that the same mechanism may be used for different sized garages, the only change being in the length of the cords or chains, the body of the mechanism, however, remaining the same irrespective of the size of the garage. The main body of the device constitutes a single unit which is shipped and installed as a unitary structure.

60 Although this invention has been described in considerable detail, it is to be understood that such description is intended as illustrative rather than limiting, as the invention may be variously embodied and is to be interrupted as claimed.

I claim:

1. In a door opening and closing mechanism, a pair of doors, guiding means, a main carriage carried on said guiding means and operatively connected to said doors to open and close said doors as said carriage moves back and forth along said guiding means, an auxiliary carriage movable simultaneously with said main carriage, power means for moving said main carriage in one direction to open said doors, power means moving said auxiliary carriage in the reverse direction with a greater force than said first power means to close said doors, means normally connecting said main carriage and said auxiliary carriage, and means for detaching said main carriage from said auxiliary carriage. 15

2. In a door opening and closing mechanism, a pair of doors, guiding means, a main carriage carried on said guiding means and operatively connected to said doors to open and close said doors as said carriage moves forward and backward along said guiding means, an auxiliary carriage carried on said guiding means, means temporarily connecting said auxiliary and main carriages, power means for moving said main carriage in a forward direction to open said doors, power means for moving said auxiliary carriage in the reverse direction with a greater force than said first power means to close said doors, detachable latching means for locking said main 20 and auxiliary carriages in their forward positions, and means for releasing said detachable latching means. 25

3. In a door opening and closing mechanism, a pair of doors, guiding means, a main carriage carried on said guiding means and operatively connected to said doors to open and close said doors as said carriage moves forward and backward along said guiding means, an auxiliary carriage carried on said guiding means, means temporarily connecting said auxiliary and main carriages, power means for moving said main carriage in a forward direction to open said doors, power means for moving said auxiliary carriage in the reverse direction with a greater force than said first power means to close said doors, detachable latching means for locking said main and auxiliary carriages in their forward positions, means for releasing said detachable latching means, and means for detaching said main carriage from said auxiliary carriage when said carriages are at the rear end of their strokes. 30

4. In a door opening and closing mechanism, a pair of doors, guiding means, a main carriage carried on said guiding means and operatively connected to said doors to open and close said doors as said carriage moves forward and backward along said guiding means, an auxiliary carriage carried on said guiding means, means temporarily connecting said auxiliary and main carriages, power means for moving said main carriage in a forward direction to open said doors, power means for moving said auxiliary carriage in the reverse direction with a greater force than said first power means to close said doors, detachable latching means for locking said main and auxiliary carriages in their forward positions, means for releasing said detachable latching means, and bumper means operable from an automobile and mounted exteriorly of said doors 40 for detaching said main carriage from said auxiliary carriage when said carriages are at the rear ends of their strokes. 45

5. In a door opening and closing mechanism, a pair of doors, guiding means, a main carriage 50

- carried on said guiding means and operatively connected to said doors to open and close said doors as said carriage moves forward and backward along said guiding means, an auxiliary carriage carried on said guiding means, means temporarily connecting said auxiliary and main carriages power means for moving said main carriage in a forward direction to open said doors, power means for moving said auxiliary carriage 5 in the reverse direction with a greater force than said first power means to close said doors, detachable latching means for locking said main and auxiliary carriages in their forward positions, door locking means for locking said doors in closed position, means for simultaneously releasing said door locking means and detaching said main carriage from said auxiliary carriage, and pull cord means operable exteriorly of said doors when said doors are open for releasing the detachable latching means, whereby said carriages will move rearwardly to close said doors, said pull cord means including means for providing slack in the pull cord for allowing the pull cord to be drawn a material distance from the doors before said pull cord means operates and for taking up the slack before the doors close. 10
- 15 9. In a device of the class described, a garage, said garage having doors, door closing means including power means for storing power when said doors are manually opened, latching means for temporarily locking said doors open, pull cord means for releasing said latching means, said pull cord means including a pull cord and slack 15 take up means for preventing the release of said latching means until the slack has been removed from said pull cord, whereby said pull cord may be operated by the driver of an automobile while said automobile moves outwardly clear of said doors, said slack take up means retracting said pull cord within said garage upon the release of said pull cord prior to the closing of said doors. 20
- 20 10. In a door opening and closing mechanism, a pair of doors, guiding means, a main carriage carried on said guiding means and operatively connected to said doors to open and close said doors as said carriage moves forward and backward along said guiding means, an auxiliary carriage carried on said guiding means, means temporarily connecting said auxiliary and main carriages, power means for moving said main carriage in a forward direction to open said doors, power means for moving said auxiliary carriage in the reverse direction with a greater force than 25 said first power means to close said doors, detachable latching means for locking said main and auxiliary carriages in their forward positions, means for releasing said detachable latching means, door locking means for locking said doors in closed position, and means for simultaneously releasing said door locking means and detaching said main carriage from said auxiliary carriage. 30
- 25 7. In a door opening and closing mechanism, a pair of doors, guiding means, a main carriage carried on said guiding means and operatively connected to said doors to open and close said doors as said carriage moves forward and backward along said guiding means, an auxiliary carriage carried on said guiding means, means temporarily connecting said auxiliary and main carriages, power means for moving said main carriage in a forward direction to open said doors, power means for moving said auxiliary carriage in the reverse direction with a greater force than 35 said first power means to close said doors, detachable latching means for locking said main and auxiliary carriages in their forward positions, dash pot means for delaying the final opening motion of said doors, and means for releasing 40 said detachable latching means. 45
- 30 11. In a door opening and closing mechanism, a pair of doors, guiding means, a main carriage carried on said guiding means and operatively connected to said doors to open and close said doors as said carriage moves forward and backward along said guiding means, an auxiliary carriage carried on said guiding means, means temporarily connecting said auxiliary and main carriages, power means for moving said main carriage in a forward direction to open said doors, power means for moving said auxiliary carriage in the reverse direction with a greater force than 45 said first power means to close said doors, detachable latching means for locking said main and auxiliary carriages in their forward positions, door locking means for locking said doors in closed position, means for simultaneously releasing said door locking means and detaching said main carriage from said auxiliary carriage, and pull cord means operable exteriorly of said doors when said doors are open for releasing the detachable latching means, whereby said carriages will move 50 rearwardly to close said doors. 55
- 35 8. In a door opening and closing mechanism, a pair of doors, guiding means, a main carriage carried on said guiding means and operatively connected to said doors to open and close said doors as said carriage moves forward and backward along said guiding means, an auxiliary carriage carried on said guiding means, means temporarily connecting said auxiliary and main carriages, power means for moving said main carriage in a forward direction to open said doors, power means for moving said auxiliary carriage in the reverse direction with a greater force than 60 said first power means to close said doors, detachable latching means for locking said main and auxiliary carriages in their forward positions, door locking means for locking said doors closed, and means operable by an automobile externally of said doors for detaching said main carriage from said auxiliary carriage and for releasing 65 said door locking means. 70
- 40 12. In a door opening and closing mechanism, a pair of doors, guiding means, a main carriage carried on said guiding means and operatively connected to said doors to open and close said doors as said carriage moves forward and backward along said guiding means, an auxiliary carriage carried on said guiding means, means temporarily connecting said auxiliary and main carriages, power means for moving said main carriage in a forward direction to open said doors, power means for moving said auxiliary carriage in the reverse direction with a greater force than 75 said first power means to close said doors, detachable latching means for locking said main and auxiliary carriages in their forward positions, door locking means for locking said doors closed, and means operable by an automobile externally of said doors for detaching said main carriage from said auxiliary carriage and for releasing said door locking means. 75

doors as said carriage moves forward and backward along said guiding means, an auxiliary carriage carried on said guiding means, means temporarily connecting said auxiliary and main carriages, power means for moving said main carriage in a forward direction to open said doors, power means for moving said auxiliary carriage in the reverse direction with a greater force than said first power means to close said doors, detachable latching means for locking said main and auxiliary carriage in their forward positions, door locking means for locking said doors closed, means operable by an automobile externally of said doors for detaching said main carriage from said auxiliary carriage and for releasing said door locking means, and means for holding said door locking means in released position during the initial opening motion of said doors and for releasing said door locking means during the final opening motion of said doors.

13. In a door opening and closing mechanism, a pair of doors, guiding means, a main carriage carried on said guiding means and operatively connected to said doors to open and close said doors as said carriage moves forward and backward along said guiding means, an auxiliary carriage carried on said guiding means, means temporarily connecting said auxiliary and main carriages, power means for moving said main carriage in a forward direction to open said doors, power means for moving said auxiliary carriage in the reverse direction with a greater force than said first power means to close said doors, detachable latching means for locking said main and auxiliary carriages in their forward positions, means for releasing said detachable latching means, and suspension means and lateral adjustment means for supporting and laterally adjusting said guiding means.

14. In a door opening and closing mechanism, a pair of doors, guiding means, a main carriage guided by said guiding means, a pair of links extending from said main carriage to said doors for opening said doors when said main carriage moves forwardly and for closing said doors when said main carriage moves backwardly, an auxiliary carriage guided by said guiding means, a first latching means carried by said main carriage for temporarily engaging said auxiliary carriage to temporarily lock said carriages together, power means for moving said main carriage in a forward direction, power means for moving said auxiliary carriage in a rearward direction with a greater force than said first power means, a second latching means carried by said main carriage for locking said main carriage in its forward position, and tripping means for selectively tripping said first and second mentioned latching means.

15. In a door opening and closing mechanism, a pair of doors, guiding means, a main carriage guided by said guiding means, a pair of links extending from said main carriage to said doors for opening said doors when said main carriage moves forwardly and for closing said doors when said main carriage moves backwardly, an auxiliary carriage guided by said guiding means, a first latching means carried by said main carriage for temporarily engaging said auxiliary carriage to temporarily lock said carriages together, power means for moving said main carriage in a forward direction, power means for moving said auxiliary carriage in a rearward direction with a greater force than said first power means, a sec-

ond latching means carried by said main carriage for locking said main carriage in its forward position, pull cord means for releasing said second latching means, and means carried by and externally of said doors for releasing said first mentioned latching means. 5

16. In a door opening and closing mechanism, a pair of doors, guiding means, a main carriage guided by said guiding means, a pair of links extending from said main carriage to said doors for opening said doors when said main carriage moves forwardly and for closing said doors when said main carriage moves backwardly, an auxiliary carriage guided by said guiding means, a first latching means carried by said main carriage for temporarily engaging said auxiliary carriage to temporarily lock said carriages together, power means for moving said main carriage in a forward direction, power means for moving said auxiliary carriage in a rearward direction with a greater force than said first power means, a second latching means carried by said main carriage for locking said main carriage in its forward position, pull cord means including a pull cord adapted to be drawn outwardly past said doors when said doors are open for tripping said second latching means and including pull cord retracting means for retracting said pull cord prior to the closing of said doors, and bumper means adapted to be actuated by an automobile 10 15 20 25 30 35 for releasing said first mentioned latching means.

17. In a door opening and closing mechanism, a pair of doors, guiding means, a main carriage carried by said guiding means, links connecting said main carriage with said doors to open said doors when said main carriage moves forwardly and to close said doors when said main carriage moves rearwardly, an auxiliary carriage carried by said guiding means, said main carriage having a first latch means for temporarily engaging said auxiliary carriage and having a second latch means for locking said main carriage and said auxiliary carriage in a forward position, simultaneously operable tripping means carried by said guiding means for tripping said first latch means when said main carriage is in its rear position and for tripping said second latch means when said main carriage is in its forward position, and means for operating said tripping means. 40 45 50

18. In a door opening and closing mechanism, at least one door, guiding means, a carriage carried on said guiding means and operatively connected to said door to open and close said door as said carriage moves back and forth along said guiding means, power means for moving said carriage back and forth along said guiding means, latching means for latching said carriage against rearward door closing motion, a pull cord having one end connected to said latching means and having the other end constituting a manipulating end and normally hanging down adjacent and inwardly of said door, and quick operating slack take-up means for said pull cord comprising a weighted pulley over which said pull cord is looped, whereby the manipulating end of said pull cord may be grasped by the operator and drawn outwardly a material distance while the door is open to trip said latching means and whereby upon release of said pull cord said pull cord will be retracted prior to the closing of said door. 55 60 65 70
